OVEN FOR DOMESTIC RANGES

Thomas E. Taylor, Cleveland, Ohio, assignor to
The Cleveland Cooperative Stove Company,
Cleveland, Ohio, a corporation of Ohio

Application August 25, 1937, Serial No. 160,841

5 Claims. (Cl. 126—273)

This invention relates to an oven for domestic cooking ranges of gas and electric type.

One of the principal objects of the present invention is to provide an oven having exaggerated differences in temperature at different portions of the oven floor and compartment so that a number of different foods, each of which requires a different condition for cooking, may be placed in the oven simultaneously and cooked to the proper degree in the same interval of time.

More specific objects are to provide an oven in which the heating effects, while different at different portions, are maintained uniform at the particular portions respectively, in which the heat is retained more efficiently, and in which heat is concentrated at localized floor areas, the temperature at the points of concentration being greatly in excess of the temperatures at other portions of the oven.

Another specific and equally important object is to provide an oven in which substantially all common household foods may be cooked thoroughly at temperatures below the scorching temperature of the particular foods, and may be maintained in the oven for a period of several hours without danger of overcooking.

Another object is to provide an oven in which the heat from the heating source is applied substantially directly to localized areas of the floor which are offset from the mid-portion of the floor and in which heating media from the source enter the oven by convection at zones remote from the floor areas of concentrated heat.

Another object is to provide vents in the oven near the lower level of the floor and remote from the floor areas of heat concentration and from the zone of introduction of the heating media so that the heated portions circulate entirely through the oven preparatory to discharge therefrom.

Another object is to apply heat directly to the oven floor near a forward corner thereof and cause heating media to flow from the zone of application beneath the floor level in a manner providing a gradually decrescent temperature on the floor in a direction away from the source of heat, and to cause the heated products to enter the oven compartment directly at a zone remote from the zone of application of heat to the floor and to discharge the products at a zone remote from their point of introduction into the oven compartment.

Other objects and advantages will become apparent from the following specification, wherein reference is made to the drawings in which—

Figure 1 is a fragmentary front elevation of a gas cooking range having an oven and burner combination embodying the principles of the present invention, the oven being shown in section for clearness in illustration, along the line 1—1 in Figure 2.

Figure 2 is a vertical sectional view taken on the plane indicated by the line 2—2 of Figure 1.

Figure 3 is a fragmentary sectional view taken on a plane indicated by the line 3—3 of Figure 1.

The present invention is useful, both in connection with gas-heated ovens and electric ovens, but, for the purposes of illustration, a gas-heated oven only will be described.

In the form illustrated, the oven compartment 1 is incorporated in a gas cooking range 2, and is provided with the usual inner side walls or liners 3, a top wall 4, and a rear wall 5, the front of the oven being closed by the usual door 6. The floor of the oven is preferably in the form of a removable sheet metal panel 7 supported on brackets 8 which extend horizontally fore and aft of the oven compartment. Beneath the panel 7 and in spaced relation thereto, is a supplemental panel 9 which, with the panel 7, defines a passage 25 for products of combustion or heating media from the burner or source of heat into the oven compartment 1.

In the form illustrated, the oven is heated by a small or low-capacity gas burner 10 which is positioned near the front right-hand corner of the oven compartment beneath the floor or panel 7 thereof, and which discharges into the space between the panels 7 and 9. The burner is preferably arranged to discharge a fan-shaped flame 35 rearwardly between the panels 7 and 9 toward the rear wall of the oven. Interposed between the burner 10 and the under side of the panel 7 is a cast-iron plate 12 for effecting more uniform distribution of the heat from the small concentrating burner over a larger localized area of the floor.

At the margin of the oven compartment opposite from the burner, there is provided between the panel 7 and the side wall 3 a suitable passage 13 for the products of combustion from the burner or heating media from an electric heating element, if such is used. This passage preferably is provided by indenting the liner 3 adjacent the bracket 8, this indentation extending vertically or about one-half of the height of the liner 3 so as to assure a rapid rise of the products of combustion discharged through the passage 13. The plate 12 may be spaced very slightly below the under surface of the panel 7 so as to render the heat discharged therefrom 55

and onto the panel more nearly uniform over the localized area of application onto the floor of the oven. Due to the position of the burner and its direction of discharge between the panels 7 and 8, the heated products pass rearwardly toward the right rear corner of the oven, as illustrated in Figure 3, and upon filling of the space between the channels tends to diffuse and flow as a gradually expanding curtain to the passage 13, at which point the heated products are distributed substantially uniformly fore and aft of the oven compartment. These products rise rapidly along the liner 3 toward the top of the compartment due to convection currents. If the oven were vented near its upper limit, in the customary manner, however, sufficient heat could not be supplied by the burner 10 to maintain the cooking temperature in the oven regardless of the time of exposure to the food thereto. The present oven, however, is provided with exhaust passages 15 in the rear wall substantially at or slightly above the floor of the oven or top surface of the panel 7. The exhaust passages 15 are at the same side of the oven as the burner 10 and 25 at the rear wall thereof so that the heated products from the burner necessarily must pass the entire width of the oven floor and upwardly through the oven and entirely therearound to the vents. Since the hot gases necessarily rise 30 relative to the unheated gases, the heated gases cannot escape from the oven until their heat is substantially dissipated or until they have been forced out by additional hot gases from the burner 10. Consequently, with a very small 35 burner, the heat is retained for a sufficient period so that the entire oven may be raised to a slow cooking temperature. At about half way of the height of the oven compartment and also at about two-thirds the height thereof are provided brackets 40 16 and 17, respectively, the brackets being arranged in pairs, one bracket of each pair being on each of the side liners of the oven. Each pair of brackets is arranged to slidably receive and support a grill shelf 18 which, due to its 45 adjustability in height, may be arranged to expose the foods to the higher temperature near the top of the oven or lower temperatures near the vertical mid-portion of the oven. A suitable stack 20 leads from the exhaust passages 15 to the usual discharge flue of the range. Regardless of the type of burner or heating element used it is apparent that the oven floor is heated to the highest temperature at the front right-hand corner portion, that is, directly over the 50 burner, this area of higher temperature being substantially co-extensive with the plate 12 and provided with a "hot spot". Beginning at this zone or location, the temperature of the floor is gradually decrescent rearwardly and laterally toward the side opposite from the burner, the left rear corner generally being the least heated portion of the floor. In the oven compartment itself, the temperature effected, due to the flow of heated products of combustion or other heating 55 media, is greatest on the shelf 18 directly over the passage 13, this temperature being gradually decrescent in the direction transversely of the oven away from the passage 13 and then downwardly toward the discharge passages 15. Obviously, so long as gases at cooking temperature are admitted through the passage 13, the upper strata of the gases in the oven compartment are maintained at the proper temperature, the temperature being gradually decrescent downward 60 until they approach the zone of heat application

overlying the plate 12. At this zone part of these gases are additionally heated by radiation and tend to rise immediately and thus prevent too rapid a discharge thereof and loss of heat from the oven. Furthermore, due to the bottom 5 venting of the oven, considerable moisture is partially entrapped and maintained above the floor level, or, more particularly, above the level of the passages 15, thus preventing drying out of the foods being cooked. The oven is preferably operated at a temperature of about 175° F. at the level of the shelf 18 and at this location the usual thermostatic control element may be installed. With the maintenance of 175° F. temperature at the vertical mid-portion of the oven, the temperatures throughout the remainder thereof are such as are required for substantially all foods customarily used and the temperatures at various zones in the oven are so related that a large number of the customary foods may be 20 placed in the oven in the proper localities at the same time subjected to the oven heat for the same period without over or under cooking any one of the foods. The burner 10 is usually so adjusted that, the oven being adjusted to maintain this 25 temperature constantly, all of the foods can be cooked for a period of from eight to ten hours without danger of overcooking. The burner may be adjusted, however, for a more rapid cooking, if desired, and substantially the same relation 30 between the various portions of the compartment will be maintained. This temperature recited, however, is below the scorching temperature except at or adjacent the floor area of concentration of the burner heat. In case an electric 35 heating element is used the heat therefrom may be distributed by the upper configuration of the heating element itself and the plate 12 accordingly eliminated. Thus the oven floor is provided with a concentrated heat zone or "hot spot" 40 with a temperature decrescent in all directions therefrom. The foods cooked are arranged in the oven in suitably covered receptacles, each cover having a small vent for the escape of vapor or gases developed in cooking. Foods requiring 45 a higher temperature or a longer cooking period are disposed on the floor level adjacent the zone of heat concentration, that is, the zone overlying the plate 12. Those requiring progressively less temperature may be placed on the bottom at 50 distances from the heat concentration zone proportional to the required cooking temperatures. The foods requiring still lower temperatures are placed on the shelf 18, as shown, in order from left to right in Figure 1, those requiring less heat 55 being placed further from the left. For maintaining foods in warm condition after cooking, they may be disposed on the floor of the oven near the front center, and the burner reduced to provide about 150° F. at the rear mid-portion of the 60 shelf 18.

The heat flow at the shelf level is substantially as described but there is much less variation in temperature for different portions, the heating of the oven at the left, due to the introduction of 65 gases at the left of the oven, being somewhat balanced by heat radiated from the floor at the right and at the floor area of heat concentration.

It should be noted that the floor 7 is flat and 70 free from any appreciable protuberances so that the cooking receptacles rest directly thereon and heat is transferred to the bottoms of the receptacles by substantially entirely direct conduction instead of by convection across air spaces 75

between the bottoms of the receptacles and the floor.

This relation is important as it makes possible the use of a lower capacity burner and affords more accurate control of heat applied to the receptacles at different portions of the oven floor.

Having thus described my invention, I claim:

1. The combination with a domestic cooking oven comprising an oven compartment having enclosing walls including a movable door and a heat-conducting substantially imperforate floor which is slidably supported for removal and replacement through said door, of heating means arranged to concentrate heat on a relatively limited area of the floor offset from the mid-portion of the floor and to maintain the floor in heated condition at gradually decrescent temperatures in a direction away from the area of concentrated heat.

2. An oven comprising a closed compartment having a heat conducting, substantially imperforate floor member slidably supported in the compartment for removal therefrom and replacement therein and on which receptacles for food can be directly supported, the compartment having side, top and rear walls, the side walls having guides for the floor member, a burner beneath the floor member in closely spaced relation thereto, a heat absorbing and distributing relatively heavy metal plate interposed between the burner and the floor member and in very slightly spaced relation to the under side of the floor member for concentrating the heat from the burner at a localized zone of the floor member and applying said heat substantially uniformly throughout said zone.

3. In a domestic cooking oven comprising an oven compartment having enclosing walls and a heat-conducting floor, a low-capacity heating means positioned to concentrate heat on a relatively limited area of the floor, and means arranged for conducting gaseous media along the under side of the floor, thence directly into the oven compartment at one enclosing wall, and thence out of the compartment at another enclosing wall remote from the first wall and at a low elevation in the compartment for progressively

constraining heated media from the heating means from discharge from the oven compartment until the heat thereof is so dissipated into the oven that the heated media discharged is at substantially the lowest temperature of the heated media in the oven compartment.

4. An oven comprising a closed compartment having side, top and rear walls, a burner beneath the floor in closely spaced relation thereto, a heat absorbing and distributing metal plate interposed between the burner and the floor and in very slightly spaced relation to the under side of the floor for concentrating heat from the burner at a localized zone of the oven floor and for applying said heat substantially uniformly throughout said zone, said zone being positioned in spaced relation to the mid-portion of the oven floor, means beneath the floor providing therewith a conduit for products of combustion from said burner and discharging into the oven compartment at a zone remote from said zone of heat concentration, exhaust passages in one of the walls of the compartment remote from the point of introduction of the products of combustion, and a shelf supported in the compartment above the vertical mid-portion of the oven compartment.

5. An oven comprising a closed compartment having side, top and rear walls, a burner beneath the floor in closely spaced relation thereto, a heat absorbing and distributing metal plate interposed between the burner and the floor and in very slightly spaced relation to the under side of the floor for concentrating heat from the burner at a localized zone of the oven floor and for applying said heat substantially uniformly throughout said zone, said zone being positioned in spaced relation to the mid-portion of the oven floor, means beneath the floor and providing therewith a conduit for products of combustion from said burner and discharging into the oven compartment upwardly and at a zone remote from said zone of heat concentration, and exhaust passages in one of the walls of the compartment near the floor level and remote from the point of introduction of the products of combustion into the compartment.

THOMAS E. TAYLOR.
